GENERATING APPARATUS

Thomas J. Rees, Reno, Nev.

Application April 15, 1937, Serial No. 137,109

2 Claims. (Cl. 60—46)

This invention relates to a generating apparatus and has for its object to provide, in a manner as hereinafter set forth, an apparatus of the class referred to whereby the products of combustion of hydrogen and oxygen are employed in connection with heated water vapor for the purpose of generating super-heated steam to be employed as a driving medium for rotary and reciprocatory engines.

10 A further object of the invention is to provide, in a manner as hereinafter set forth, an apparatus of the class referred to including means to burn a fuel such as hydrogen and oxygen gases at constant pressure within a combustion chamber in the generation of steam.

15 A further object of the invention is to provide, in a manner as hereinafter set forth, an apparatus of the class referred to including a combustion chamber and means for introducing combustible gases under high pressure into said chamber and with said means so formed to prevent the mixing of the gases prior to the combustion point thereby safeguarding against pre-ignition.

20 A further object of the invention is to provide, in a manner as hereinafter set forth, an apparatus including a combustion chamber, a burner opening therewith, means for delivering combustible gases in a non-mixed state through the burner tip into said chamber and at an angle to the point of combustion to form a flame travelling in a direction to create a vacuum surrounding the burner tip to prevent the latter being burned and deteriorated.

25 Further objects of the invention are to provide, an apparatus of the class referred to which is comparatively simple in its construction and arrangement, strong, durable, compact, thoroughly efficient in its use for the purpose intended there-40 by, readily assembled and comparatively inexpensive to set up.

30 With the foregoing and other objects in view, the invention consists of the novel construction, combination and arrangement of parts as will be 45 more specifically referred to and as illustrated in the accompanying drawings wherein is shown an embodiment of the invention, but it is to be understood that changes, variations and modifications may be resorted to which fall within 50 the scope of the invention as claimed.

In the drawings:

Figure 1 is a side elevation of the apparatus,

Figure 2 is a fragmentary view partly in elevation and partly in vertical section,

55 Figure 3 is a section on line 3—3, Figure 2,

Figure 4 is a fragmentary view in sectional plan of the housing and combustion chamber forming element,

Figure 5 is a fragmentary view in vertical section upon an enlarged scale of that portion of the apparatus for generating the energy medium,

Figure 6 is a detail in vertical section of the lower portion of the oxygen supply pipe,

Figure 7 is a section on line 7—7, Figure 6, and

Figure 8 is a section on line 8—8, Figure 5.

The apparatus includes a water reservoir 10, a pump 11, a water intake pipe 12 leading from reservoir 10 to pump 11, an engine 13 of the stator and rotor type of known form having its power transmitting shaft 14 extending from opposite ends of the stator, a reduction gearing 15 of known form, a housing 16 arranged over the engine 13, a water pressure tank 17 arranged above pump 11, a water supply line 18 leading from pump 11 to tank 17 and having interposed therein a valve controlled by-pass 19 leading therefrom to the top of reservoir 10, a valve controlled water feed line 20 extended from tank 17 and provided with a pair of spaced nozzles 21 of the water vaporizing type opening into an expansion chamber 22 within the housing, a burner 23 opening into a combustion chamber 24 within the housing, an oxygen gas tank 25, a valve controlled feed line 26 leading from the latter and 30 opening into the chamber 24 in proximity to the upper end of the latter, a hydrogen gas tank 27, a valve controlled feed line 28 leading from tank 27 passing through the burner 23 and opening into the combustion chamber 24, a return pipe 29 leading from engine 13 to the reservoir 10, a support 30 for reservoir 10, and a transmission shaft 31 extended from the reduction gearing 15. The latter is associated with and operated with one of the extended portions of the shaft 14. The other 40 extended portion of the shaft 14 passes through the pump 11. The operating shaft for pump 11 is indicated at 32 and is driven from a transmission 33 leading from shaft 14 to shaft 32. A bearing 34 is provided for one end of shaft 14. 45 The tank 17 has a pressure gage 35.

The housing 16 comprises a hollow substantially globular outer casing 36 of metallic material formed of oppositely disposed superimposed, hollow upper and lower portions of semi-globular 50 contour. Each of said portions consists of a pair of abutting parts and with one of the parts being flanged for overlapping the other. The upper and the lower portion of the casing 36 will be formed of two parts in the manner as is shown 55

in Figure 3 relative to the upper portion of the casing. The upper and lower portions of the casing 36 will be hereinafter referred to as upper and lower sections, a hollow substantially globular metallic inner casing 37 spaced from casing 36 and a body of insulation material 37^a interposed between said casings. The casing 36 at its top and bottom is formed with aligned openings 39, 39 and said openings are intersected at their axes by the vertical median of casing 36. The latter at its bottom is provided with a depending collar 40 having its inner face forming a continuation of the wall of opening 39. The casing 36 is formed of a pair of oppositely disposed hollow superimposed sections 41, 42 substantially of like form and provided with laterally extended annular flanges 43, 44 respectively. The flange 43 overlaps the flange 44. The body of the casing 36 is of less thickness than the body of the casing 37.

The casing 37, which provides the expansion chamber 22, is formed with a pair of aligned openings 45, 46 respectively which have their axes intersected by the vertical median thereof. The opening 45 is of materially greater diameter than opening 46. The casing 37 is formed of a pair of oppositely disposed hollow superimposed sections 47, 48 provided with laterally extending apertured abutting annular flanges 49, 50 respectively. The flange 49 is provided with an annular groove 51 in its lower face. The flange 50 has its upper face formed with an annular rib 52 which extends into the groove 51. The sections 47, 48 are detachably anchored together by the holdfast means 52^a. The opening 45 is in the section 47 and has its wall of two different diameters to form a shoulder 53. The portion of largest diameter of the wall of opening 45 is of less length than the portion of smallest diameter and is the lower portion of such wall. The top of section 47 is provided with an annular boss 54 having its inner face forming a flush continuation of the portion of smallest diameter of the wall of opening 45. The section 47 has as an integral part thereof an energy medium conducting element 55 which depends from the bottom of said section, communicates with the expansion chamber 22 through the opening 46 and leads to and discharges into the engine 13 for supplying the energy medium thereto. The latter is in the form of superheated steam.

The element 55 is in the form of a tubular member 56 having an intermediate portion 57, an upper portion 58 of reduced diameter with respect to portion 57 and a tapered lower portion 59. The member 56 axially thereof is formed with a conducting channel 60 having its wall forming a flush continuation of the wall of opening 46. The channel 60 extends from one end to the other end of element 55. The lower end of channel 60 is closed by a plug 61 which has threaded engagement with the wall of the channel. The lower end of the portion 57 of member 56 is formed with a pair of oppositely extending openings 62 communicating at their inner ends with the channel 60 and having their outer ends flush with the outer periphery of portion 57. Secured within the openings 62 are a pair of oppositely disposed nozzles 63 having the inner part of their inner faces tapered, as at 64 and the outer parts of their inner faces flared as at 65. The said outer parts are of greater length than said inner parts. These latter open into the channel 60. The portion 57 of member 56 is formed with a laterally extended apertured annular flange 66 which

seats on an enlarged circular portion 67 formed on the top of the stator of engine 13. The flange 66 is anchored to engine 13 by the holdfast means 68. The element 55 extends into the engine 13. The portion 58 of member 56 extends through the insulation 37^a, opening 39 and collar 40.

Suspended within and from the casing 37 is a hollow casting 69 which in vertical section is substantially of heart or inverted pear shaped contour and in horizontal section of annular contour. The casting 69 includes a hollow body part 70 having a threaded opening 75 axially of its upper end and an opening 76 axially of its lower end, a tubular upstanding stem 71 integral with the outer face of the top of body part 70 and which surrounds and has its inner face offset with respect to the wall of the opening 75 and an inferiorly threaded depending collar 72 integral with the outer face of the bottom of body part 70 and which has its inner face forming a continuation of the wall of the opening 76. There is associated with the collar 72, a threaded plug 77 for closing the opening 76. The body part 70, in connection with the plug 77 forms the combustion chamber 24. The latter has a closed lower end and its upper end formed to receive the inner end of the burner structure 23 which opens into the chamber 24. In cross section the upper portion 73 of body part 70 is in the form of a segment of a circle and the lower portion 74 of body part 70 is flared. The portion 74 is of greater height than portion 73. The body part 70 is spaced completely from the wall of the expansion chamber 22. The space between the upper portion 73 of body part 70 and the wall of expansion chamber 22 is less than the space between the lower portion 74 of body part 70 and the wall of the expansion chamber 22. The portions 73, 74 of body part 70 form respectively the upper and lower portions of the combustion chamber 24. The lower portion of the chamber 24 decreases in diameter from the upper to the lower end of portion 24 of body part 70. The stem 71 is of uniform inner diameter. The stem 71 is formed with upper and lower parts 77, 78 respectively. The part 77 is of reduced outer diameter with respect to the outer diameter of part 78 whereby at the junction of said parts the stem 71 is formed with a peripheral shoulder 79. The part 77 at its upper portion is threaded on its outer periphery as at 80. The upper portion of part 78 extends into the opening 45, the shoulder 79 abuts shoulder 53, the part 77 extends through the opening 45 and through and above boss 54. Engaging with threads 80 is a nut 81 which seats on boss 54 and in connection with the latter, part 77 and shoulders 53, 79, not only clamps casting 69 to casing 37 but further suspends the body part 70 in the expansion chamber 22 in spaced relation to the wall of the latter. The portion 74 of the body part 70 is formed with an upper row of spaced sidewise aligned inclined ports 82 and a lower row of spaced sidewise aligned inclined ports 83. The ports 82 are arranged substantially at the transverse median of the portion 74 of body part 70. The ports 83 are arranged in proximity to the opening 76. The ports 82, 83 establish communication between the combustion chamber 24 and the expansion chamber 22 for the passage of the products of combustion from a combusted mixture within the combustion chamber to the expansion chamber. A pair of spaced catalytic elements 84 are suspended from the upper part of the portion 73 of the body part 70 within the upper portion of the combustion chamber.

The burner or burner structure 23 includes a vertical tubular outer sleeve 85 formed of an outer portion 86 and an inner portion 87. The portion 86 is of greater inner and outer diameter with respect to that of portion 87. The latter is formed at its inner end with an inwardly extending annular flange 88. The outer periphery of portion 87 is formed with screw threads. The inner periphery of portion 86 of sleeve 85 is provided with screw threads. The junction of the portions 86, 87 forms the sleeve 85 with an internal shoulder 89. The sleeve 85 constitutes a holder and threadedly engages at its inner end terminal portion with the threads of opening 75 in body part 70 of casting 69 whereby the burner and casting are connected together.

The burner 23 opens into the combustion chamber 24 and its inner end is termed a tip. Seated upon the flange 88 is a disc 90 formed with an axial opening 91 and a row of spaced oppositely inclined ports 92 surrounding opening 91. Extending into the sleeve 85 and bearing against disc 90 is a tubular clamping member 93 which also constitutes a hydrogen gas conducting means. The ports 92 provide intakes for the hydrogen gas to the combustion chamber 24. The inner end of member 93 is open. The outer end of member 93 is closed by a head 94 formed axially with a threaded opening 95. The side of member 93 in proximity to head 94 has an opening 96 and an integral lateral nipple 97 which registers with opening 95. The hydrogen gas feed line 28 is coupled as at 97^a to the nipple 97. The member 93 includes an outer and an inner portion 98, 99 respectively. The portion 98 is of greater outer diameter than portion 99 and is formed on its outer periphery with screw threads which coact with the threads on portion 86 of sleeve 85 for connecting member 93 and the sleeve together. The outer diameter of portion 99 of member 93 is such as to snugly engage the inner face of portion 87 of sleeve 85. The junction of the portions 98, 99 of the member 93 provides the outer periphery of the latter with a shoulder 100 which coacts with the shoulder 89 for confining a packing 101, under a compressed state within sleeve 85 and between said shoulders. Threadedly engaging with the wall of opening 95 of head 94 is the enlarged threaded outer end 102 of an oxygen gas conductor 103 which is of a length to extend through the axial opening 91 of disc 90 into the combustion chamber 24. The conductor 103 at its outer end 102 is coupled as at 104 to the oxygen gas feed line 26. The conductor 103 is formed of an inner and an outer tubular section 105, 106 respectively (Figure 6) which are threadedly connected together and with the inner section 105 provided with a reduced outer end portion which extends into the inner end of the outer section 106. The inner end of the inner section 105 is closed, as at 107 and formed at such end axially thereof with a depending lug 108. The inner section 105 in proximity to its closed inner end 107 is formed with spaced downwardly inclined ports 109 which open into the upper end of the combustion chamber 24 and constitute intakes for the oxygen gas for chamber 24.

The nozzles 21 are oppositely inclined and of like form. Each nozzle extends through the section 41 of casing 36, through insulation 37^a and into section 47 of the casing 37. The inner or discharge end of each nozzle is flush with the inner face of section 47. The nozzles are directed to spaced points of the outer face of the portion 73 of the body part 70 of casting 69. A

spark plug 110 is arranged in the body of the housing, extends across the expansion chamber 22 and through casting 69 into the combustion chamber 24.

The structure as aforesaid includes a hydrogen gas conducting means which is the member 93 and an oxygen gas conducting means which is the element 103. The member 93 and element 103 are arranged in concentric spaced relation and closed to each other whereby the gases are not mixed until they reach the combustion chamber 24 for ignition. The oxygen gas is delivered at a point below the delivery of the hydrogen gas and substantially in a direction to intersect the hydrogen gas on the delivery of the latter.

The cross section contour of the casting 69, which forms the combustion chamber, provides when the pressure within the generator is nearly equal to the injected fuel pressure, thereby making it possible to operate at close pressure differences, that is, the difference between the injected fuel pressure and the pressure within the generator as it has been found that the nearer the pressure difference the higher the efficiency obtained.

The ports in the body part 70 of the casting 69 provide for the spraying of the products of combustion from the combustion chamber into the expansion chamber. The latter is for the reception of vaporized water which is injected by pump pressure to contact the upper part of the outer face of the portion 73 of body part 70 and as the said portion 73 is of high temperature a superheated vapor is formed and into the vapor the products of combustion from the hydrogen and oxygen gases are sprayed, thus forming a driving medium of superheated steam.

The apparatus includes means to burn a fuel such as hydrogen and oxygen gases at constant pressure within a combustion chamber.

The orifices for the passage of fuel, water and steam are so formed and so related as to coact so that the percentage of fuel and water injected generates an energy medium of a quality corresponding to the predetermined operating temperature and pressure.

The term heart shape is to be considered as generic to heart shape and to inverted pear shape.

When assembling casings 36, 37 and casting 69, the parts of the lower portion or section of the casing 36 are positioned about the section 48 of casing 37 in a manner whereby the said lower portion or section of casing 36 will appear as shown in Figure 2. Casting 69 is then mounted in section 48 of casing 37, after which section 47 of casing 37 is mounted on and secured to section 48. The casting 69 is then suspended from section 47. Prior to securing sections 47, 48 together, insulating material is packed between said section 47 and the lower portion or section of casing 36. After section 47 has been secured to section 48 the elements 21 are attached to casing 37; then the insulating material 37^a is positioned to envelope the section 47 and the parts of the upper portion or section of the casing 36 are arranged in the manner as shown in Figure 2. The upper and lower portions or sections of casing 36 are then secured together, and the structure will appear as shown by Figure 2.

What I claim is:

1. In a steam generating apparatus, an upstanding casting including a hollow body part of heart-shaped contour in vertical section and of annular contour in cross section, said body part being formed with a threaded opening axially of

its upper end, an upstanding tubular peripherally shouldered stem integral at its lower end with the top of said body part surrounding and offset with respect to said opening, said body part formed of a flared lower portion closed at its lower end and an upper portion of less height than said lower portion and of segmental contour in cross section, said portions providing a combustion chamber having its intake formed by said opening, means 5 providing a vertically disposed expansion chamber of globular form having an outlet at its lower end, an opening at the upper end of the expansion chamber and an annular boss forming an upward continuation of the wall of said opening, said stem extending upwardly through said opening provided by said means, the wall of said expansion chamber completely encompassing in spaced relation said body part, said lower portion in proximity to the axis of its lower end 10 being formed with a circumferential row of spaced downwardly disposed outwardly inclined ports and above and in proximity to said row formed with a circumferential row of spaced downwardly disposed outwardly inclined ports, 15 said rows of ports establishing communication between the lower portion of the said chambers, means for injecting water vapor under pressure 20 against the outer face of the upper portion of the body part, means adjustably engaging with said stem and bearing against the top of said structure for suspending said body part within the expansion chamber, means mounted in the 25 stem for delivering a combustible fuel into the upper portion of the combustion chamber, a combustion supporting agent delivering means extending through and depending from the delivering means for delivering a combustion supporting 30 agent in the combustion chamber at a point below the delivery of the fuel, means engaging with the wall of said opening for connecting the delivering means with the upper portion of said body part, and spaced means carried by the 35 upper portion of said body part for combusting the delivered fuel.

2. In a steam generating apparatus, an upstanding casting including a hollow body part of heart-shaped contour in vertical section and of annular contour in cross section, said body part

being formed with a threaded opening axially of its upper end, an upstanding tubular stem integral at its lower end with the top of said body part and surrounding said opening, said body part formed of a flared lower portion closed at 5 its lower end and an upper portion of less height than said lower portion and of segmental contour in cross section, said portions providing a combustion chamber having its intake formed by said opening, a structure providing a vertically disposed expansion chamber of globular form having an outlet at its lower end, said stem extending upwardly through the top of and peripherally abutting intermediate its ends said structure, the 10 wall of said expansion chamber completely encompassing in spaced relation said body part, said lower portion in proximity to the axis of its lower end being formed with a circumferential row of spaced downwardly disposed outwardly inclined ports and above and in proximity to said row formed with a circumferential row of spaced 15 downwardly disposed outwardly inclined ports, said rows of ports establishing communication between the lower portion of the said chambers, means for injecting water vapor under pressure 20 against the outer face of the upper portion of the body part, means adjustably engaging with said stem and bearing against the top of said structure for suspending said body part within the expansion chamber, means mounted in the 25 stem for delivering a combustible fuel into the upper portion of the combustion chamber, a combustion supporting agent delivering means extending through and depending from the delivering means for delivering a combustion supporting 30 agent in the combustion chamber at a point below the delivery of the fuel, means engaging with the wall of said opening for connecting the delivering means with the upper portion of said body part, and spaced means carried by the 35 upper portion of said body part for combusting the delivered fuel.

THOMAS J. REES.
